UNITED STATES PATENT OFFICE.

RAYMOND W. SEELYE, OF BRAINERD, MINNESOTA, ASSIGNOR TO AUTO TOOL CO., OF SANDPOINT, IDAHO.

COMBINATION-TOOL.

1,326,108.

Specification of Letters Patent. Patented Dec. 23, 1919.

Application filed February 7, 1919. Serial No. 275,591.

To all whom it may concern:

Be it known that I, RAYMOND W. SEELYE, a citizen of the United States, and resident of Brainerd, county of Crow Wing, and 5 State of Minnesota, have invented certain new and useful Improvements in Combination-Tools, of which the following is a specification.

The present invention relates to a tool 10 of the compound type, and aims to provide a novel and improved implement combining a shovel, pick, hoe, or mattock, and hammer, and consisting of a minimum number of parts, in order that the tool can be 15 readily carried or transported in small space.

The tool is intended particularly for use by tourists, prospectors, bushmen, and the like, in order that they may carry the unitary tool instead of a number of individual 20 tools, the construction being such that the tool can be quickly converted for use either as a shovel, pick, hoe, or mattock, or as a hammer.

Another object is the provision of such a 25 tool using but a single handle and having novel means for the attachment of the handle in different positions when using the tool for different purposes.

A further object is the provision of a 30 combination tool having a head provided with an opening to receive the handle when using the tool as a pick, hammer, mattock, or hoe, and novel means whereby the handle 35 can be applied to the head and pick or similar blade when the tool is used as a shovel, to provide a substantial construction in either position of the handle.

A still further object is the provision of 40 novel means for interchangeably attaching to the head, a shovel blade and hammer member.

It is also the object of the invention to 45 provide a novel assemblage of the component elements, requiring but a simple and inexpensive construction, with a minimum number of parts, and providing for a practical, serviceable and efficient combination tool of the nature indicated.

With the foregoing and other objects in 50 view which will be apparent as the description proceeds, the invention resides in the construction and arrangement of parts hereinafter described and claimed, it being un-

derstood that changes can be made within 55 the scope of what is claimed without departing from the spirit of the invention.

The invention is illustrated in the accompanying drawings, wherein:—

Figure 1 is a plan view of the tool as 60 used as a shovel;

Fig. 2 is a side elevation thereof;

Fig. 3 is a cross-section on the line 3—3 of Fig. 1;

Fig. 4 is a longitudinal section taken on 65 the line 4—4 of Fig. 1;

Figs. 5 and 6 are cross-sections taken on the respective lines 5—5 and 6—6 of Fig. 1;

Fig. 7 is a side elevation of the tool as 70 used as a pick and mattock or hoe, portions of the handle being broken away;

Fig. 8 is an outside face view of the tool with the parts as shown in Fig. 7;

Fig. 9 is a view similar to Fig. 7, showing the shovel blade removed and the hammer member substituted therefor; and 75

Figs. 10 and 11 are cross-sections on the respective lines 10—10 and 11—11 of Fig. 9.

In carrying out the invention, there is provided a metallic head 1 which can be 80 cast, forged or otherwise manufactured, said head having a transverse socket 2 provided with an opening or eye 3 therethrough, preferably of elliptical form. This opening is similar to that used on ordinary picks 85 and like tools, and the head 1 terminates at one end in a pick blade 4 or its equivalent, while at the opposite end, the head terminates in an attaching shank 5 of arcuate cross-section, with the concaved side facing 90 outwardly. The end of the shank 5 is reduced and tapered to a point, as at 6.

The shovel blade 7 may be of any suitable construction, being preferably stamped from sheet-metal, and having at its rear 95 edge, a roll 8 struck therefrom, and merging at its forward end into the body of the blade. A socket piece 9 is riveted or otherwise secured on the blade 7 and is of arched form, said piece 9 overhanging the 100 forward end of the roll 8 and forming a socket to snugly receive the point 6 of the shank 5, with the roll 8 fitting snugly within said shank and the shank abutting the rear end of the piece 9, as seen in Fig. 4. 105 Thus, the shank 5 straddles the roll 8 and the end of the shank fits snugly in the socket, to provide a rigid joint, and a bolt

10 or other securing element is engaged through apertures in the shank 5 and roll 8 to clamp said parts together.

A wooden or other suitable handle is provided, and if same is of wood, it is preferably provided with a sleeve 12 on its outer end to reinforce the same. This sleeve 12 is of a shape to fit snugly in the opening 3, and is tapered inwardly. The outer end 5 of the handle 11 and sleeve 12 is of concaved shape as at 13, so as to fit the side of the socket 2 adjacent to the pick blade 4, and the pick blade and handle fit snugly together, as seen in Fig. 2, when they are 10 assembled for using as a shovel. Said outer end of the handle has a hook or finger 14 projecting therefrom to be inserted through an aperture 15 in one side of the socket 2 adjacent to the pick blade 4. Thus, the 15 hook can be inserted through the aperture 15 by a swinging movement, when the handle 11 and pick blade 4 are swung together, thus locking said parts together against longitudinal separation, since the hook 14 20 cannot pull straight out through the aperture 15.

A clamping band 16 is used on the handle 11 and the same is slidable thereon, and has an offset portion 17 to receive and sit astride 25 the pick blade 4, and a bolt 18 or other tightening member for clamping said band on the handle. Thus, when the handle and head are assembled, and the handle and pick blade swung together, the band 16 can be 30 slipped onto the handle and over the blade 4, and the band then tightened on the handle, which will hold said handle and blade 4 tightly together, to use the tool as a shovel, it being noted that the blade 4 will brace the 35 handle 11 and take up the strains, so that there is little tendency for the handle to break. This provides a very substantial shovel. By loosening the band 16 and slipping it off of the blade 4, said blade and 40 handle can be swung apart, to withdraw the hook 14 from the head 1. Then by removing the band 16 from the handle, said handle can be inserted inwardly through the opening 3 until the sleeve 12 is drawn into said 45 opening with a wedge fit, thus bringing the handle at right angles to the head instead of in alinement or parallel therewith, as when the tool is used as a shovel. Then, by again placing the band 16 on the handle and moving it against the socket 2 and tightening said band, it will serve to hold the handle 50 11 firmly in place in the head, thereby preventing it from coming loose when using the tool as a pick, mattock, or hoe, as seen in 55 Figs. 7 and 9. This also provides a substantial construction.

In order that the tool can be used as a hammer also, a separate hammer member 19 is provided, and the same can be readily carried in the pocket; while the tool proper is

carried, as seen in Figs. 1 and 2, as a single implement, or as a shovel which can be easily converted into a pick, mattock, or hoe by simply changing the handle with respect to the head as above explained. The hammer member 19 is a block of metal of suitable size and shape, and provided with a recess 20 extending into the same from its rear end, said rear end of the member 19 being provided with an extension 21 of arcuate 70 cross-section similar to the roll 8 of the blade 7, so as to fit the shank 5 of the head 1 in the same manner, while the tip 6 of the shank enters the recess 20 in the same manner as it entered the socket of the blade 7. 75 The same bolt 10 is used for clamping the extension or portion 21 of the member 19 to the shank 5. The blade 7 and hammer 19 can thus be used interchangeably as conditions may require. 80

Having thus described the invention, what is claimed as new is:—

1. A combination tool having a head provided with an opening and a blade extending therefrom, a handle to fit against said blade and abut said head and also insertible lengthwise said opening at an angle with the blade to bring one end within said opening, and a clamp slidable on the handle to engage either the blade or inner side of the head for securing the handle to said blade or head in its corresponding positions. 90

2. A combination tool comprising a head having an opening and a shovel blade and a pick blade at its opposite ends, a handle 100 adapted to bear against the pick blade and abut the head at one end and to be inserted in said opening at an angle with said blade, and means for attaching said handle to said pick blade and said end of the handle in 105 abutment to the head.

3. A combination tool having a head provided with an opening and a blade, a handle having one end formed to fit in said opening with the handle at an angle with said blade, 110 said handle being adapted to fit against said blade in another position and said end of the handle being shaped to abut the head, said head and handle having interengageable portions to lock them together in abutment when the handle and blade are fitted together, and means for clamping said handle and blade together. 115

4. A combination tool comprising a head having a socket and a blade, a handle to fit 120 against said blade in one position and having one terminal shaped to fit in said socket in another position, said terminal being shaped to abut and fit said socket when the handle is fitted against said blade, said terminal of the handle and socket having portions to interengage and lock them together in abutment when the handle and blade are fitted together, and a clamp for the handle engageable with the blade to clamp them to- 125 130

gether, and to also fit against the socket when the handle is fitted therein.

5. A combination tool comprising a head having a socket with an opening there-
5 through, and a pick blade, a handle having one terminal shaped to fit in said opening, said handle being arranged to fit said blade, and said terminal of the handle being shaped to abut against said socket, the
10 socket having an aperture at one side, and said terminal of the handle having a hook to engage through said aperture when the handle and blade are swung together, and a clamp to fit on the handle and engage said
15 blade for clamping them together, and to also fit against said socket to hold the handle in said opening.

6. A combination tool comprising a head having a pick blade and a shovel blade at opposite ends, a handle adapted to bear 20 against and extend along the pick blade, said head and handle having means for attaching them together in abutment with the handle bearing against the pick blade and also having means for securing the handle in 25 the head at an angle with said blades, and a clamp slideable on the handle to embrace the pick blade when the handle bears against it, or to bear against the head when the handle is inserted therein to hold them against sep- 30 aration.

In testimony whereof I hereunto set my hand.

RAYMOND W. SEELYE.
